PERFUME ATOMIZER OR SIMILAR ARTICLE

William A. Cotter, New York, N. Y., assignor to
Cotter Manufacturing Co., Inc., New York, N. Y.

Application December 26, 1947, Serial No. 143,357

Term of patent 14 years

(Cl. D83—1)

To all whom it may concern:

Be it known that I, William A. Cotter, a citizen of the United States, residing at New York city, in the county of New York and State of New York, have invented a new, original, and ornamental Design for a Perfume Atomizer or Similar Article, of which the following is a specification, reference being had to the accompanying drawing, forming part thereof.

In the drawing:

Fig. 1 is a side elevational view of a perfume atomizer, showing the cap in closed position, embodying my new design.

Fig. 2 is a side elevational view thereof, showing the cap in the open position;

Fig. 3 is a front elevational view thereof, showing the cap in the open position;

Fig. 4 is a top plan view thereof, showing the cap in closed position;

Fig. 5 is a top plan view thereof, showing the cap in the open position;

Fig. 6 is a front elevational view thereof, showing the cap in the closed position; and

Fig. 7 is a bottom plan view thereof.

I claim:

The ornamental design for a perfume atomizer or similar article, as shown.

WILLIAM A. COTTER.
